UNITED STATES PATENT OFFICE

147,386

DESIGN FOR A TELEPHONE CHAIR

Glenn Thomas, Toledo, Ohio

Application April 8, 1946, Serial No. 128,401

Term of patent 14 years

(Cl. D15—1)

To all whom it may concern:

Be it known that I, Glenn Thomas, a citizen of the United States, residing at Toledo, in the county of Lucas and State of Ohio, have invented a new, original, and ornamental Design for a Telephone Chair, of which the following is a specification, reference being had to the accompanying drawings, forming a part thereof.

Figure I is a perspective view showing the front and upper surface of the telephone chair of my new design.

I claim:

The ornamental design for a telephone chair, as shown.

GLENN THOMAS.
